UNITED STATES PATENT OFFICE.

ALFRED C. O. BOCK, OF BROOKLYN, NEW YORK, ASSIGNOR TO THE YALE & TOWNE MANUFACTURING COMPANY, OF STAMFORD, CONNECTICUT.

LOCK.

1,377,658.

Specification of Letters Patent. Patented May 10, 1921.

Application filed September 3, 1920. Serial No. 408,009.

To all whom it may concern:

Be it known that I, ALFRED C. O. Bock, a subject of Germany, and a resident of Brooklyn, in the county of Kings and State 5 of New York, have invented certain new and useful Improvements in Locks; and I do hereby declare the following to be a full, clear, and exact description of the invention, such as will enable others skilled in the art 10 to which it appertains to make and use the same.

My invention relates to an improvement in locks, the object being to provide bolt mechanism constructed to interlock with the 15 strike plate or keeper so as to prevent a separation of these parts by jimmying or otherwise and also to provide means for reinforcing and deadlocking the said bolt members so that when the door is locked the said 20 interlocking members cannot be disengaged from the strike plate or keeper except by the proper manipulation of the bolt actuating mechanism.

With these and other objects in view my 25 invention consists in the parts and combination of parts, and in the details of construction as will be more fully explained and pointed out in the claims:

In the accompanying drawings; Figure 1 30 is a view in elevation of the lock with the cover plate removed, the bolts being shown in projected position; Fig. 2 is a similar view showing the bolts retracted; Fig. 3 is a view in transverse section on the line $\alpha-\alpha$ 35 of Fig. 1; Fig. 4 is a view in transverse section; Fig. 5 is a view in end elevation with the bolts projected; Fig. 6 is a view of the dead locking bolt; Fig. 7 is a view of one 40 of the L-shaped bolts and Fig. 8 is a view of a dead locking bolt and one of the L-shaped bolts, the former being broken away to show the shoulder 17.

10 represents the lock casing and 11 the strike plate or keeper provided with an 45 opening to receive the bolt mechanism of the lock and adapted to be overlapped by the said bolt mechanism. The face plate 12 of the casing 10 is provided with a rectangular opening for the passage and free 50 movements of the bolt 13 which latter are hook shaped and are pivotally mounted on pins 14 secured to the casing. These pins are located adjacent the ends of the slot 55 15 the end plate 12 of the casing, and the bolts 13 which are mounted on said pins

are L-shaped and so located that when they are turned inwardly or retracted, their free ends rest adjacent each other at the center as shown in Fig. 2 and flush or approximately so with the outer face of the casing 60 10, and when turned to locking position, their free ends which are at right angles to their bodies, overhang the end walls of the bolt opening in the keeper and lock the keeper to the lock and absolutely prevent 65 the said parts from being separated by a jimmy or other tool.

Each bolt is provided with a curved tail piece 16 integral with the body of the bolt and curved inwardly toward each other and 70 engaging shoulders 17, which in the present instance are shown as screws, on the dead locking bolt 18 the latter being recessed at its sides to receive the curved tail pieces.

When the L or hooked shaped bolts 13 75 are in their retracted or housed position as shown in Fig. 2, the dead locking bolt 18 rests against the latter as shown, and the curved tail pieces of the bolts rest against the shoulders on the dead locking bolt so 80 that the bolts 13 and dead locking bolt 18 are so located and connected that when one moves outwardly the other moves in the same direction. This dead locking bolt is as wide as the space between the two L- 85 shaped bolts when the latter are projected as shown in Fig. 1, and is so coupled to the latter by the curved tail pieces as previously explained, that the movements imparted to the dead locking bolt 18 by the actuating springs 19 of the latter and also by the knob and key actuated mechanism, are transmitted to the L-shaped bolts so that the latter are controlled in their movements by the movements of the dead locking bolt. 90 This latter bolt is provided with two rearwardly projecting stems 20 which pass through the cross bar 21, the latter bearing at its ends against the shoulders 22 and yieldingly held against the latter by the 100 springs 19 embracing the stems 20. These springs bear at their ends respectively against the inner end of the dead locking bolt 18 and the cross bar 21 and tend to force said bolt outwardly. 105

As the L-shaped bolts are pivoted and are moved in both directions by the dead locking bolt, and as the latter is forced outwardly by the springs 19 it follows that means must be provided for holding the L- 110

shaped bolts in their retracted positions. The means I employ consists of a trip lever 23 pivoted at its inner end to the inner surface of the casing and provided at its outer end with a shouldered head 24 located in a plane in front of the rim or outer edge of the lock casing and adapted to overlap the free ends of the members 13^a of the L-shaped bolts and hold them within the casing. This trip lever 23 is yieldingly forced toward the bolt by a spring 25 located in the pocket 26 which projects from the inner or rear face of the casing 10, and is moved rearwardly by its contact with the strike plate 11 during the act of closing the door. As the door approaches the jamb carrying the strike plate or keeper, the latter engages the head 24 of the trip lever 23 and forces it rearwardly thus moving the head out of the plane of the L-shaped bolts 13 and permitting the springs 19 to force the dead locking bolt 18 outwardly. As the latter moves outwardly its contact with the bodies of the L-shaped bolts turns the latter outwardly, and the dead locking bolt 18 then continuing its movement outwardly between the two L-shaped bolts as shown in Fig. 1, absolutely locks them against movement except by the knob 27 or key mechanism 28 of the lock.

One stem 20 of the dead locking bolt is provided with a shoe 29 which is engaged by the lever 30 on the knob shank 31 for retracting the stem and its connected dead locking bolt and the said lever 30 is provided with a projecting stud 32 which is in position to be engaged by the key actuated mechanism in the usual and well known manner.

The dead-locking bolt 18 is, when projected normally held in such position against inward pressure applied to the exposed or projecting part thereof by the dogging lever 33 pivoted to the inner face of the lock casing and so located that when the dead locking bolt is projected the outer free end of said lever will be turned into the plane of movement of the said bolt and thus prevent it from being pushed in by pressure applied to the exposed end of same. This dogging lever 33 is moved in one direction by a spring and is provided adjacent its pivot 34 with a laterally projecting toe 35 which is actuated by the shoulders 36 and 37 formed on the hub 38 of lever 33. When the bolts are projected, the toe 35 rests within the recess between the shoulders 36 and 37, the shoulders 36 operating in its movement to shift the lever to its dogging position. When the lever 30 on the knob shank is moved in a direction to retract the dead locking bolt and also the L-shaped bolts, which latter as previously explained are actuated by the deadlocking bolt, the shoulder 37 on said lever engaging the rear side of the toe

35 shifts the dogging lever 33 to one side of the path of movement of the dead locking bolt thus leaving the latter free to be retracted.

The shape of the curved tail pieces 16 of the L-shaped bolts are such that after the dead locking bolt has thrown the L-shaped bolt to locking position, the dead locking bolt will then be free to move outwardly without interference and without further movement of the L-shaped bolts until its outer end is approximately in a plane with the outer end of the L-shaped bolts thus not only acting as a reinforce for the L-shaped bolts, but as a main bolt for the lock, the L-shaped bolts operating mainly to tie the lock to the keeper 11 so as to prevent a separation of these parts. In retracting the bolts the dead-locking bolt moves inwardly a sufficient distance to permit the L-shaped bolts to turn before engaging the curved tail pieces, which, as before explained, are then engaged by the shoulders 17 on the deadlocking, and the continued inward movement of the latter then operates to turn and release the L-shaped bolts from the keeper.

The lock mechanism may be actuated by a knob, and also by a key mechanism from the outer side of the door in the usual manner.

It is evident that many slight changes might be resorted to in the relative arrangement of the parts shown and described without departing from the spirit and scope of my invention hence, I would have it understood that I do not wish to confine myself to the exact construction and arrangement of parts shown and described but,

Having fully described my invention what I claim as new and desire to secure by Letters Patent, is:—

1. In a lock, the combination of a casing, two L-shaped bolts pivoted thereto, and a dead locking bolt for positively actuating both of said L-shaped bolts and adapted to be projected between and reinforce them and also enter the keeper and perform the function of a latch bolt, and means for actuating the dead locking bolt.

2. In a lock, the combination of a casing, the L-shaped bolts pivoted thereto, each bolt having a curved extension or tail piece, a spring projected dead locking bolt mounted to slide between and dead lock said L-shaped bolts, and provided with shoulders for engaging the curved tail pieces on the L-shaped bolts for retracting the latter, the said dead-locking bolt adapted to be projected between the L-shaped bolts and into the keeper and perform the function of an ordinary latch bolt, a stem secured to said dead locking bolt, and means for retracting the latter.

3. In a lock, the combination with a casing, a keeper, two L-shaped bolts pivoted to the casing, each having a curved extension

or tail piece, a spring projected dead locking bolt having shoulders engaging the curved extensions on the L-shaped bolts, the connection between the curved extensions of the L-shaped bolts and the shoulders on the dead locking bolt being such that the latter has free movement outward to its projected position within the keeper and movement inwardly sufficiently to clear or be free of the L-shaped bolts before engaging the curved extensions for retracting the L-shaped bolts, and means for retracting the latter.

4. In a lock, the combination of a casing, a keeper, an L-shaped bolt pivoted to the casing and having a curved end extension or tail piece, a spring projected dead locking bolt having a shoulder to engage said curved extension and adapted to enter the keeper and reinforce the L-shaped bolt, means for dogging the dead locking bolt and means for retracting the bolt and also for shifting the dogging means out of the path of the dead locking bolt.

5. In a lock, the combination of a casing, a keeper, an L-shaped bolt pivoted to the casing and provided with a curved tail piece, a spring projected dead locking bolt having a shoulder to engage the tail piece on the L-shaped bolt, the said dead locking bolt having a limited movement independently of the L-shaped bolt whereby it can enter the keeper and be withdrawn from the latter without actuating the L-shaped bolt, and means for retracting the dead locking bolt.

6. In a lock, the combination of a casing, 35 a keeper, a dead locking bolt having a shoulder, an L-shaped bolt pivoted to the casing and adapted to be projected and retracted by the dead locking bolt, the said L-shaped bolt having a curved tail piece engaged by 40 the shoulder on the dead locking bolt, a dogging lever for the dead locking bolt and key and knob actuated means for shifting the dogging lever out of the path of movement of the dead locking bolt and for re- 45 tracting the latter.

7. In a lock, the combination of a keeper, a casing, two L-shaped bolts pivoted thereto, a spring projected dead locking bolt bearing against the L-shaped bolts for moving 50 the latter into locking position, a trip lever carried by the locking casing and having a head adapted to overlap the L-shaped bolts and hold them retracted the said head adapted to be engaged by the keeper and moved 55 out of the path of said bolts, connections between the L-shaped bolts and dead locking bolt whereby the former will be retracted by the latter and means for retracting the dead locking bolt.

In testimony whereof, I have signed this specification in the presence of two subscribing witnesses.

ALFRED C. O. BOCK.
